Primary Examiner — Katrina N Gonzalez

(57) **CLAIM**

The ornamental design for the cat litter box as shown and described.

DESCRIPTION

FIG. 1 is a front, right, and top perspective view of the cat litter box, showing my design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of an encircled area labeled “9” in FIG. 2.

The broken lines depict portions of the cat litter box that form no part of the claimed design. The dot-dash broken lines shown in FIGS. 2, and 9 framing portions of the cat litter box for enlargements purposes form no part of the claimed design.

1 Claim, 9 Drawing Sheets
